UNITED STATES PATENT OFFICE.

GEORGE HERBERT WHITTINGHAM, OF NEW YORK, N. Y., ASSIGNOR TO AUTOMATIC SWITCH COMPANY OF BALTIMORE CITY, A CORPORATION OF MARYLAND.

DEVICE FOR AUTOMATICALLY CUTTING OUT STARTING RESISTANCES OF ELECTRIC MOTORS.

SPECIFICATION forming part of Letters Patent No. 728,814, dated May 19, 1903.

Application filed July 8, 1902. Renewed April 15, 1903. Serial No. 152,801. (No model.)

To all whom it may concern:

Be it known that I, GEORGE HERBERT WHITTINGHAM, a citizen of the United States, residing at New York, State of New York, have ⁵ invented certain new and useful Improvements in Devices for Automatically Cutting Out Starting Resistances of Electric Motors, of which the following is a specification.

This invention relates to improvements in ¹⁰ automatic starting devices for electric motors, which have for their object to gradually reduce the resistance in the armature-circuit of the motor automatically when the current is turned on and the motor starting by cutting out the coils of resistance one after the ¹⁵ other from that of the greatest resistance to that of the least resistance and maintaining it in this position during the running of the motor, so that when the circuit through the ²⁰ motor is first completed to start the motor the current will meet with the greatest resistance and when the motor is fully running there will be the least resistance to the passage of the current. When the current is ²⁵ shut off, this controlling device operates to automatically replace the resistance in the circuit in readiness to be started again.

The object of the invention is to provide ³⁰ an improved device of this character in which a clutch device driven directly or indirectly by a motor moves the contact for the starting resistance from the point of high resistance toward the point of low resistance and automatically releases said contact at a ³⁵ desired point, thereby throwing the clutch entirely out of service and relieving it from any further work or undue friction while the motor is running.

Reference is to be had to the accompanying ⁴⁰ drawings, in which—

Figure 1 is a diagrammatic view illustrating one arrangement in which the principles of the invention may be carried out, and Fig. ⁴⁵ 2 is a detail transverse sectional view of the clutch device employed in the present instance merely for the purpose of illustrating the invention.

Referring to the drawings, Fig. 1, the letter

a designates an electric motor; *b*, an electromagnetic clutch device; *c*, the starting resistance for the motor, and *d* a switch of any suitable construction adapted to open and close the line-circuit. The shunt-field of the motor *a* is energized by a wire *e*, secured to one side of the switch *d* and extending therefrom to a binding-post or similar connecting-point *f*, and also by a wire *e'*, extending from said post *f* back to the other side of said switch. Also to the post *f*, as illustrated in Fig. 1, is secured a wire *g*, passing to a pivot-post *h*, and from thence through the helix *i* of the electromagnetic clutch device *b* to one end of a helix *j*, coiled around a soft-iron core *k*, and forming with said core a retaining-magnet *l*, whose purpose will be ⁵⁵ presently described. One end of the winding of said helix is connected directly to or grounded on the iron of the magnet-core *k*, and the other end of said helix is secured to a wire *m*, which passes through a permanent resistance ⁶⁰ *n* back to the line-circuit.

The starting resistance *c* is mounted on a suitable base, with its low-resistance end contiguous to the retaining-magnet *l*, and to said end is secured a wire *o*, which passes through ⁷⁵ the motor-armature and joins at *p* the return-wire *e'* of the shunt-field, so that it is connected to one side of the line-circuit, as illustrated.

The electromagnetic clutch device *b* in this ⁸⁰ instance comprises a cup-shaped disk *q*, provided on its periphery with teeth *q'*, meshing with a worm *r'* on the armature-shaft *r*, and said disk is mounted to rotate on an axis *s*, rigidly secured to a base-plate *s'*. The wire ⁸⁵ forming the helix *i* of the said electromagnet is wound around a spool *i'*, rigidly supported on said base-plate *s'*, and is located within said disk. A keeper *t* is also mounted on said axis *s* so as to turn thereon in either direction, and said keeper is in contact with the circular rim or face *q*² of the disk *q*, whereby it may be gripped by said disk when the latter is energized. To the free end of said keeper *t* is connected a link *u'*, which in turn ⁹⁰ is connected to a contact-arm *u*, pivoted at

one end to the pivot-post *h* and carrying at its other end a brush-contact adapted to sweep step by step over the contact-plates of the starting resistance *c* when the said arm is 5 moved.

In practical operation when the line-circuit is closed the current flows in the direction of the darts, Fig. 1, from the line to the point *f*, where it divides and a portion flows through 10 the shunt-field and thence back to the line. The other portion of the current flows from the point *f* to the pivot-post *h*, where it again divides, a portion thereof flowing through the clutch device to energize the same and thence 15 back to the line through the retaining-magnet and permanent resistance, and the other portion thereof flowing through the contact-arm *u*, the starting resistance *c*, and thence through the armature back to the line. When the 20 motor starts by the closing of the line-circuit, its armature rotates the disk *q* of the clutch device, which has been energized by the current just described and has therefore attracted and gripped to it the keeper *t*, and 25 said rotation of the disk thus draws the contact-arm *u* upwardly, cutting out the starting resistance until the point of lowest resistance has been reached, at which point said arm abuts against the core of the retaining-magnet 30 *l*, thereby short-circuiting and deenergizing the clutch device by making direct contact with the grounded end of the helix *j* of the retaining-magnet. Thus the keeper *t* is released, and the disk *q* is allowed to rotate 35 freely, relieving said disk from any further work or undue friction while the motor is running. The magnet *l* retains the contact-arm *u* at the low-resistance end of the starting resistance until the line-circuit is opened 40 to stop the motor, when said arm moves back automatically to its starting position either by gravity or any suitable means, such as a spring *v*.

While in the accompanying drawings the 45 clutch-disk *q* is shown in direct connection with the motor-armature, it is manifest that various intermediate connections may be substituted for said direct connection to effect the rotation of said disk. For instance, in 50 elevator-service the winding-drum of the elevator might drive the said disk by means of a gear or chain, or the disk may be rotated entirely independent of the said motor.

While in the accompanying drawings is 55 illustrated one method of deenergizing the magnet of the clutch device—namely, by short-circuiting—it is to be understood that other methods also may be employed to accomplish this result without departing from 60 the scope of the invention as defined in the appended claims.

Having thus fully described my invention, what I claim, and desire to secure by Letters Patent, is—

65 1. The combination of a motor; a contact governing the admission of current to the mo-

tor; a clutch device actuated by the current to make connection with said contact; means for moving said clutch device whereby to move said contact and vary the strength of the current passing through the motor; and means for deenergizing said clutch device to release it from said contact. 70

2. The combination of a motor; a contact governing the admission of current to the motor; a clutch device actuated by the current and driven by the motor to operate said contact and vary the strength of the current passing through the motor; and means for deenergizing said clutch device by the movement of said contact. 75

3. The combination of a motor; a contact governing the admission of current to the motor; a clutch device actuated by the current and driven by the motor to operate said contact and vary the strength of the current passing through the motor; means whereby at one point in its movement said contact will deenergize said clutch device so as to release itself therefrom; and means for returning 90 said contact to its starting position. 85

4. The combination of a motor; a starting resistance for the same; a contact adapted to cut said starting resistance in and out; a clutch device operated by the motor for moving said contact; and means for deenergizing said clutch device and retaining the contact in the position it has reached when the clutch device is deenergized. 95

5. The combination of a motor; a starting 100 resistance for the same; a contact for cutting said resistance in and out; a clutch device adapted to grip said contact by electromagnetic influence and driven by said motor to move said contact; and means for short-circuiting said clutch device whereby to deenergize the same and release it from said contact. 105

6. The combination of a motor; a starting 110 resistance for the same; a contact adapted to cut said starting resistance in and out; a clutch device operated by the motor for moving said contact; means for deenergizing said clutch device; mechanism for retaining the contact when the clutch device is deenergized; and means for automatically returning 115 said contact to its starting position. 110

7. The combination of a motor; an electromagnetic clutch arranged to be operated by the motor; a starting resistance and contact-plates therefor; an arm adapted to contact with said plates; a connection between said arm and said clutch whereby the latter may move the former over said plates; and a retaining-magnet connected in series with the 125 coil of the electromagnetic clutch and in a position to permit the arm to contact therewith whereby to short-circuit said clutch when the starting resistance has been cut out. 120

8. The combination of a motor; an electro- 130 magnetic clutch arranged to be operated by the motor; a starting resistance and contact-

plates therefor; an arm adapted to contact with said plates; a keeper adapted to be gripped to said clutch by magnetic influence and connected to said arm; a retaining-magnet connected in series with the coil of said magnetic clutch and in a position to permit the said arm to contact therewith whereby to short-circuit said clutch when the starting

resistance has been cut out; and means for returning said arm to its starting position. ¹⁰

In testimony whereof I affix my signature in the presence of two witnesses.

GEORGE HERBERT WHITTINGHAM.
